United States Patent Office.

DANIEL COMPTON, OF NEWPORT, NEW JERSEY.

Letters Patent No. 95,326, dated September 28, 1869.

IMPROVEMENT IN ICE-BREAKING BOATS.

The Schedule referred to in these Letters Patent and making part of the same.

To all whom it may concern:

Be it known that I, DANIEL COMPTON, of Newport, in the county of Cumberland, and in the State of New Jersey, have invented certain new and useful Improvements in Ice-Boats; and do hereby declare that the following is a full, clear, and exact description thereof, reference being had to the accompanying drawings, and to the letters of reference marked thereon.

The nature of my invention consists in the construction and general arrangement of an "ice-boat," or ice-cutter, for towing vessels and keeping the navigation open in time of ice.

In order to enable others skilled in the art to which my invention appertains, to make and use the same, I will now proceed to describe its construction and operation, referring to the annexed drawings, which form a part of this specification, and in which—

Figure 1 is a bottom view,

Figure 2, a plan view, and

Figure 3, a side view, all of one-half of the boat.

I have not deemed it necessary to represent more than one-half of the boat, as, of course, the other half is exactly similar.

In all ice-boats heretofore built, the practice has been to place the wheels so that they extend beyond the sides of the hull. When the boat has broken the ice wide enough for the passage of the hull, then the wheels must break their own way through the ice, to the manifest injury both to the wheels and to the machinery.

By practical experiments, it has been demonstrated that building ice-boats, so as to run through the ice, will not answer.

My plan is to run the vessel up on the ice, and crush it down, and then, by placing the wheels so that the hull, forward of the wheels, extend beyond their outer edge, there is no danger of inflicting any injury, neither to them nor to the machinery.

H represents the hull of my boat, which is to be

iron-plated, up to the water-line D, with suitable thickness of iron, say, of about half an inch.

S is the stem of the boat, and K, the keel, both steel-shod.

On the bottom of the boat, at the forward end, I place steel-shod runners E, F, and G, running parallel with the keel, and of suitable length.

The wheel J is placed in such a position that the forward portion of the hull extends beyond the outer edge of the wheel.

It is further provided at the sides with circular saws I, which project beyond the edge of the paddles or buckets, thus making the wheel cut the ice up as well as propel the boat.

A is the waist around the boat;

B, the deck; and

C, the cabin for the crew.

R represents railway on the deck, for ballast-cars, to increase the weight at either end, when running through heavy ice, and to assist in trimming the boat. The ballast-cars may be worked by steam from the engine.

When the boat is in operation, and is employed to open a passage through heavy ice, the forward end will run up on the ice and crush the ice down, the hull projecting beyond the outer edge of the wheels, and the saws attached to them protect them fully from all injury.

Having thus fully described my invention,

What I claim as new, and desire to secure by Letters Patent, is—

The combination of the saws I I, upon the paddles J, with the ice-breakers E F G, arranged upon the under part of the hull H, and all constructed to operate substantially as set forth.

In testimony that I claim the foregoing, I have hereunto set my hand, this 31st day of December, 1868.

Witnesses:

JAMES POWELL,

LEOPOLD EVERT.

DANIEL COMPTON.
